UNITED STATES PATENT OFFICE.

SETH WILLIAM BABBITT, OF MERIDEN, CONNECTICUT.

DESIGN FOR A CANDLESTICK.

SPECIFICATION forming part of Design No. 21,138, dated October 27, 1891.

Application filed October 2, 1891. Serial No. 407,569. Term of patent 3½ years.

To all whom it may concern:

Be it known that I, SETH WILLIAM BABBITT, of Meriden, in the county of New Haven and State of Connecticut, have invented a new Design for a Candlestick; and I do hereby declare the following, when taken in connection with accompanying drawing and the letters of reference marked thereon, to be a full, clear, and exact description of the same, and which said drawing constitutes part of this specification and represents a side view of the candlestick complete.

This invention relates to a design for a candlestick; and it consists in the configuration and ornamentation as shown in the accompanying illustration. The base A upon its upper surface curves inward and upward, and on the surface is the representation of several panels, and on the surface of the panels the representation of a border of leaves inclosing the representation of flowers. On

the standard above the base is an ornamentation represented as leaves springing outward and upward from the standard and supporting acanthus-leaves alternating with scrolls contracting in diameter upward to the standard. The socket above is in the representation of a double vase, the lower parts of which are ornamented by the representation of acanthus-leaves, the edges of the vases turned outward and terminating in scallops, as shown.

I claim—

The design for a candlestick, as described and shown in the accompanying illustration. 35

In testimony whereof I have signed this specification in the presence of two subscribing witnesses.

SETH WILLIAM BABBITT.
